DESIGN FOR A SPOON HOLDER

F. S. Matteson, Lenox, Calif.

Application March 17, 1934, Serial No. 51,087

Term of patent 7 years

To all whom it may concern:

Be it known that I, F. S. MATTESON, a citizen of the United States, residing at Lenox, in the county of Los Angeles, State of California, have invented a new, original, and ornamental Design for Spoon Holders, of which the following is a specification, reference being had to the accompanying drawing, forming part thereof.

I claim:

The ornamental design for a spoon holder, as shown.

In testimony whereof, I have hereunto set my hand at Los Angeles, California, this 10th day of March, 1934.

F. S. MATTESON.
